CLAIM

The ornamental design for a two piece breakaway traffic channelizer, as shown and described.

DESCRIPTION

FIG. 1 is a top plan view of the traffic channelizer, or the like, and showing my new design;

FIG. 2 is a bottom plan view thereof;

FIG. 3 is a front elevational view thereof;

FIG. 4 is a side elevational view thereof, the opposite side being the same as illustrated in FIG. 4;

FIG. 5 is a rear elevational view thereof;

FIG. 6 is a sectional view thereof, taken along the line 6—6 of FIG. 1;

FIG. 7 is a sectional view taken along the line 7—7 of FIG. 6;

FIG. 8 is a top-front perspective view thereof; and

FIG. 9 is a top-rear perspective view thereof.

Fig. 1.

Fig. 2.

*FIG. 3.**FIG. 4.**Fig. 5.*FIG. 6.

FIG. 7.

FIG. 8.

FIG. 9.
